UNITED STATES PATENT OFFICE.

HARRY BRIDGMAN SMITH, OF BROOKLYN, NEW YORK, ASSIGNOR TO LIGHTSHIP CLOTH BOARD CORPORATION, OF BROOKLYN, NEW YORK, A CORPORATION OF NEW YORK.

CLOTH BOARD OR SIMILAR ARTICLE.

Application filed October 18, 1923. Serial No. 669,391.

My invention relates to cloth boards, winders, or like articles constructed of fibrous sheet material such as cardboard, strawboard and paper stock.

5 The general object of the invention is to provide a very cheap, light, stiff and strong cloth board or like article, which may be and preferably is entirely free from exposed joints, seams or other irregularities, either on its broad sides or longitudinal edges, and in which the longitudinal edges present smoothly rounded surfaces which cannot injure fabrics, including the most delicate and expensive fabrics, wound upon 10 the board, and in which the ends are most desirably covered and smoothly finished by binding material, usually paper.

An important characteristic of the invention is the practically "double" structure of 20 the completed cloth board, which consists of two main portions, each of which comprises a layer or sheet of filler material which may be, and desirably is, so treated (as by corrugating) to provide maximum strength 25 and stiffness for its weight, and a facing or covering sheet applied to the filler sheet in such a way that when the two main portions are put together, there is no exposed seam or joint in the cover or facing sheets.

30 The characteristics and advantages of the invention are further sufficiently explained in connection with the following detail description of the accompanying drawing, which shows certain representative structures embodying the invention. After considering these, persons skilled in the art will understand that many variations may be made within the principles of the invention, and I contemplate the employment of any 35 structures that are proper within the scope of the appended claims.

Figure 1 is a perspective view of a completed cloth board embodying the invention in one form.

40 Figure 2 shows one of the component segments or main portions of the board, with parts broken away for explanatory purposes.

Figure 3 shows two main portions or segments of the board in process of being brought together.

45 Figure 4 shows the two main portions brought together in final position and ready for application of the end binders.

The cloth board consists principally of 55 two main portions or segments P, each of which, as best shown in Figure 2 comprises a filler sheet 1 of suitable fibrous material, such as cardboard or strawboard, and a cover or facing sheet 2. Desirably, although not 60 necessarily, the filler sheet is suitably treated to increase substantially its thickness and stiffness in proportion to its weight or normal area. This treatment consists in the 65 present instance of corrugating the filler in any suitable or known way. The particular filler 1, therefore, consists, in this specific example, of ordinary corrugated strawboard with the corrugations preferably running transversely of the longest dimensions of the 70 segment P. Facing sheet 2 may in some cases be of such material as cardboard, but usually is of paper of substantial thickness, such as a suitable grade of wrapping, or "kraft" paper. A continuous broad portion 75 2^a of the facing sheet covers one surface of the filler, and other portions 2^b of the facing sheet are folded over the longitudinal edges of the filler and adhesively secured to the opposite surface thereof. In some cases 80 the portions 2^b may be sufficiently wide to meet or even to slightly overlap, and in that case, both broad faces of the filler will be fully covered, but in many cases as here shown, for economy in material, it is preferred to make the portions 2^b relatively narrow 85 so that they extend inward only a moderate distance upon the filler.

The cover sheets are so folded or formed about the filler as to provide smoothly 90 rounded longitudinal edges 3.

The segments P may be made in the form of longitudinally continuous assemblies and cut off to provide the individual composite segments P. The method of production, 95 however, may vary greatly and is not part of the present invention.

Two of the completed segments P are now brought together after proper adhesive treatment, which may consist in applying glue, 100 as sufficiently indicated by stippling, to exposed surfaces of cover portions 2^b of one of the segments, or if desirable, both segments may have their cover surfaces so coated. The segments are brought into flat facial contact as shown in Figure 4, and the 105 surfaces 2^b are thus adhesively secured together.

While it is not always necessary to do so, it is desirable to additionally secure the segments together and to cover the more or less rough or unsightly end portions 5 of Figure 5 4. For this purpose end binders 6 are applied, as shown in Figure 1. These binders may consist of sheets or pieces of any suitable sheet material such as paper of suitable grade or 10 thickness, and in some cases they may be of fabric. Portions 6^a of the binder are adhesively secured to opposite flat faces 7 and 8 of the segments near the ends thereof, and the intermediate portions 6^b of the binders 15 cover the ends 5 of the segments and conceal them from view, and also provide a substantially smooth and flat surface which may be printed with any suitable indicia, or upon which any suitable manufacturer's 20 label may be pasted.

As will be understood from the preceding description, without elaborate explanation, the completed cloth board as shown in Figure 1, is entirely free from any surface 25 joints or irregularities. The broad surfaces 7 and 8 are smoothly covered by the integral cover sheets 2 and the edges 3 are smoothly rounded and covered with integral portions of the cover paper, so that 30 when cloth, braid or any other textiles are wound upon the boards, they do not encounter any irregularities or rough surfaces, and cannot be injured in any way. The boards are composed of cheap sheet 35 material, are very light and strong, and can be produced by rapid and economical methods, and in addition to their low cost provide great economies in shipping costs.

What I claim is:

40 1. A cloth board or the like comprising two segments each comprising filler material and a cover sheet having inturned and secured marginal portions, the segments being secured together in facial contact with the inturned marginal portions in contact and the main faces of the complete cloth board being devoid of any exposed joints or surface irregularities.

50 2. A cloth board of the like comprising two substantially similar segments each comprising filler material and a cover sheet, the segments being adhesively secured together in facial substantially flat contact and the complete cloth board having its 55 broad outer faces devoid of any exposed joints or surface irregularities, the board also having rounded longitudinal edges.

60 3. A cloth board or similar article comprising two segments, each of which includes a sheet of corrugated filler material and a cover sheet having an unbroken surface portion covering one face of the filler and marginal portions turned over and adhesively secured upon the other face of the 65 filler, and with smoothly rounded longi-

tudinal edges, the two segments being adhesively secured in facial contact with the smooth continuous cover sheet portions exposed and with the longitudinal edges of the complete board each consisting of parallel rounded edges of the two segments. 70

4. A cloth board or similar article comprising two substantially similar segments, each of which includes a sheet of corrugated filler material and a cover sheet having an unbroken portion covering one face of the filler and marginal portions turned over and adhesively secured upon the other face of the filler, and with smooth rounded longitudinal edges, the two segments being 75 adhesively secured in facial contact with the smooth continuous cover sheet portions outward and with the longitudinal edges of the complete board each consisting of parallel rounded edges of the two segments. 80

5. A cloth board or the like comprising two originally distinct and separate segments each comprising filler material and a cover sheet, the segments being secured together in facial contact and the complete 90 cloth board having its broad outer faces devoid of any exposed joints or surface irregularities, the ends of the board each including the two segment ends being covered by binders having portions adhesively secured to outer surfaces of the segment cover sheets. 95

6. A cloth board or similar article comprising two segments, each of which includes a sheet of corrugated filler material 100 and a cover sheet having an unbroken surface portion covering one face of the filler and marginal portions turned over and adhesively secured upon the other face of the filler, and with smoothly rounded longitudinal edges, the two segments being adhesively secured in facial contact with the smooth continuous cover sheet portions exposed and with the longitudinal edges of the complete board each consisting of parallel rounded edges of the two segments, the ends of the segments being covered by binding strips having portions adhesively secured to outer surfaces of the segment cover sheets. 105

7. A cloth board or similar article comprising two segments, each of which includes a sheet of corrugated filler material and a cover sheet having an unbroken surface portion covering one face of the filler 110 and marginal portions turned over and adhesively secured upon the other face of the filler, and with smoothly rounded longitudinal edges, the two segments being adhesively secured in facial contact with the smooth continuous cover sheet portions exposed and with the longitudinal edges of the complete board each consisting of parallel rounded edges of the two segments, the ends of the board being finished by binding 115 120 125 130 135

strips each of which includes a substantially flat portion overlying the ends of the segments, and other portions overlying and adhesively secured to the segment facing sheets near the ends thereof.

8. A cloth board or similar article comprising two substantially similar segments, each of which includes a sheet of corrugated filler material and a cover sheet having an unbroken portion covering one face of the filler and marginal portions turned over and adhesively secured upon the other face of the filler, and with smooth rounded longitudinal edges, the two segments being adhesively secured in facial contact with

the smooth continuous cover sheet portions outward and with the longitudinal edges of the complete board each consisting of parallel rounded edges of the two segments, the ends of the board being finished by 20 binding strips each of which includes a substantially flat portion overlying the ends of the segments, and other portions overlying and adhesively secured to the segment facing sheets near the ends thereof. 25

Signed at Brooklyn, in the county of Kings and State of New York this 5th day of Oct. A. D., 1923.

HARRY BRIDGMAN SMITH.
